BLOCK MOLDING MACHINE

Frank C. George, Orlando, Fla.

Application February 22, 1945, Serial No. 579,187

7 Claims. (Cl. 25—41)

This invention relates to a machine for molding building blocks from plastic materials, such as concrete and the like, and has for its general object to provide a simple practical machine for this purpose which is thoroughly reliable and highly efficient in operation, particularly from the standpoint of insuring a dense or closely packed condition of the material comprising the blocks.

According to one phase of the invention and to the end of insuring densification of the material comprising the blocks, the present machine includes a resiliently supported mold box and means for shaking the same to cause the loose material deposited therein to settle or densify, and in this connection a special and important object of the invention is to provide a novel, three-point, resilient suspension for the mold box whereby it is supported in proper operative position and yet is permitted to rock or tilt in different directions responsive to shaking thereof to insure rapid and most effective packing or densification of material deposited therein to form the blocks.

The mold box may be devoid of cores, in which event the formed blocks will be solid. Preferably, however, the mold box is provided with cores whereby the formed blocks are hollow, and in this connection another special and important object of the invention is to resiliently mount the cores, independently of the resilient mounting of the mold box, for rocking or tilting movements relative to the mold box in response to operation of the shaking means, to further insure rapid, effective packing or densification of the material comprising the blocks.

Another special and important object of the invention is to provide simple, practical, reliable, easily operated means for ejecting formed blocks from the mold.

Another special and important objection is to provide simple, practical means for supplying predetermined amounts of plastic material from a source of supply to the mold box.

According to the invention, the means for supplying predetermined amounts of material to the mold box includes a pan which is shiftable from a material-receiving position beyond the mold box to a position in overlying relationship to the mold box to deliver material to the latter, and in this connection another special and important object of the invention is to provide simple, practical means for releasably fastening the pan securely to the mold box in overlying relationship thereto so as to cause it to partake of shaking

movements with the mold box without any looseness and rattling relative thereto.

With the foregoing and other objects in view, which will become more fully apparent as the nature of the invention is better understood the same consists in a block molding machine embodying the novel features of construction, combination and arrangement of parts as will be hereinafter more fully described, illustrated in the accompanying drawings and defined in the appended claims.

In the accompanying drawings, wherein like characters of reference denote corresponding parts in the different views:

15 Figure 1 is a side elevation of a block molding machine constructed in accordance with one practical embodiment of the invention.

Figure 2 is a top plan view of the machine, the pan for supplying material to the mold box being shown partly in section.

Figure 3 is a vertical, longitudinal section through the machine.

Figure 4 is a transverse section through the machine; and

Figure 5 is a fragmentary end view of the machine.

Referring to the drawings in detail, A designates, generally, the frame of the machine which may be formed from angle-iron, as shown, or from any other suitable material and which may comprise, as shown, a pair of laterally spaced part, longitudinally extending lower side members 10, suitable uprights 11 rising therefrom, and a pair of laterally spaced apart, longitudinally 30 extending upper side members 12 supported by the uprights 11 and connected together by suitable transverse members 13.

The frame A is rigid and the mold box, designated generally as B, is disposed above the front end portion thereof and is resiliently supported by the same, preferably at three points, whereby it is held in proper operative position and yet is permitted to tilt or rock in different directions responsive to vibratory or shaking 45 movements imparted thereto.

While any suitable means may be employed to provide the three-point support or suspension for the mold box B, simple, practical means for this purpose may consist, as shown, of a leaf spring 14 supporting said box medially at its front end, and a pair of spring arms 15, 15 supporting said box at laterally spaced points at its rear end.

The leaf spring 14 may extend transversely of the frame A at the front end thereof and may be suitably fastened at its ends to said frame as in-

dicated at 16, so that its medial portion is free, and it may be connected medially in any suitable manner to the mold box at the front end and midway between the sides and preferably near the bottom thereof, as indicated at 17, all as shown in the drawings. On the other hand, the spring arms 15, 16 may have inturned lower ends 18 suitably fastened to the rear ends of the lower side members 10, 10 of the frame A, and inturned upper ends 19 suitably fastened to the rear end and near opposite sides of a plate 20 which is rigid with and extends rearwardly from the top of the mold box. Thus, the mold box is supported in proper operative position relative to the frame A, but obviously is free to rock or tilt slightly in various different directions when it is shaken.

While any suitable means may be provided to shake the mold box B, a simple, practical means for this purpose may comprise an eccentrically weighted shaft 21 suitably mounted on the mold box and driven by an electric motor 22 suitably mounted upon the frame A. In this connection and as illustrated in the drawings, the motor 22 may be mounted upon the upper, rear portion of the frame A; a pair of bars 23 may extend longitudinally of the machine in underlying relationship to the mold box B to which they may be welded or otherwise rigidly fastened in any suitable manner; the eccentrically weighted shaft 21 may extend transversely of the machine beyond the rear end of the mold box and may be journaled for rotation in suitable bearings carried by the rear ends of the bars 23; and a belt 24 may connect pulleys 25 and 26 on the motor shaft and said eccentrically weighted shaft, respectively, whereby the latter is driven by said motor. The shaft 21 is eccentrically weighted as indicated at 21, and responsive to rotation of said shaft the mold box obviously will be shaken due to the bars 23, upon which said shaft is mounted, being rigid with said box.

While the mold box B may be devoid of cores so that solid blocks may be formed therein, it preferably is provided with cores for forming in the blocks openings extending from side to side thereof. Moreover, while the mold box may be of a size and shape to form only a single block during a single cycle of operation of the machine, it preferably is of a size and shape to form two or more blocks during each cycle of operation of the machine. In this connection and as illustrated in the present instance, the mold box is of a size and shape to have two blocks formed therein during each cycle of operation of the machine. In other words, according to the specific construction illustrated in the present instance, said mold box is of a length to accommodate two blocks disposed in side to side relationship and extending transversely of the machine, and said box is, of course, of a width and height corresponding to the desired length and height, respectively, of the blocks. It is disposed horizontally and is closed at its sides and ends, but is open at its top and bottom. In addition, it is divided into two block-accommodating compartments by a central, vertical partition 28 extending transversely thereof.

Depending upon the desired number of openings to be formed through each block, each compartment of the mold box B may have only a single core or any desired plurality of cores disposed therein. Moreover, the core, or cores, as the case may be, may be of any desired sizes and shapes. In this connection and as illustrated in the present instance, each compartment of the mold box

5 B has therein two cores, designated as 29, which are rectangular in shape and disposed vertically and spaced equidistantly from each other and from the sides and the ends, respectively, of the compartment. Moreover, said cores are of approximately the same height as the mold box. Thus, each block has formed therein two rectangular openings extending from top to bottom thereof.

10 In accordance with the invention the cores 29 are supported resiliently relative to the mold box B for rocking or tilting movements relative thereto in response to the shaking action of the mold box produced by the eccentrically weighted shaft 21. In this connection, while said cores may be 15 resiliently mounted in any suitable manner, one simple and practical manner of resiliently mounting them is upon the bars 23 through the instrumentality of pairs of U-shaped springs 30, as best 20 shown in Figure 4 of the drawings. To each side of each core 29, medially thereof and at its bottom, is welded or otherwise suitably fastened the upper end of the outer arm of a spring 30, while to the upper ends of the two inner arms of the 25 two springs related to each core is welded or otherwise suitably fastened a connecting plate 31 which is bolted or otherwise suitably fastened to the related bar 23. Accordingly, the springs 30 in conjunction with the bars 23 serve both to 30 properly position the cores in the mold box and to resiliently support the cores for rocking or tilting movements responsive to operation of the eccentrically weighted shaft 21.

35 While the cores 26 may be of any suitable form, they preferably are of light weight, hollow, closed side and top, open-bottom form as shown.

40 To prevent material supplied to the mold box B from falling therethrough, a closure 32 is provided for the bottom of each of the two compartments of said mold box, while in order to eject finished blocks from said mold box, means is provided for moving said closures upwardly through said mold box.

45 The closures 32 are of sizes to fit the respective compartments of the mold box and, if the mold box is not provided with cores, said closures may simply be in the form of plates. If, however, the mold box is provided with cores, the closures 32 will have openings therein to accommodate the 50 cores and they will, therefore, be of grid-like form as shown. In any event, each closure 32 is mounted upon the upper ends of vertical rods 33 which extend through guide openings in the bars 23 and which, at their lower ends, are welded or otherwise suitably fastened to a common frame 34.

55 Carried by the frame 34 at opposite sides thereof are rollers 35 which are disposed between pairs of the uprights 11 whereby said frame is guided 60 for vertical movement, while underlying said rollers are pivoted cam arms 36 which, by upward and rearward swinging movements thereof, are effective to raise said rollers and thus raise the frame 34 and the closures 32 carried thereby. 65 Downward swinging movement of the cam arms is suitably limited whereby they serve as stops to predetermine the limits of downward movement of the closures 32, and when said closures are at their limits of downward movement they are disposed at the bottom of the mold box as shown. On the other hand, the cam arms are effective, when swung upwardly, to raise the closures 32 suitable distances above the top of the mold box B to completely eject formed blocks from said 70 mold box for subsequent easy removal from the

machine simply by sliding them off of said closures onto any suitable platform or support which may be provided to receive them.

The cam arms 36 may be carried by a shaft 37 extending transversely of the machine at the bottom thereof and journaled in suitable bearings carried by the lower frame members 10, and said shaft may be provided with a suitable lever arm 38 for effecting its rotation to swing said cam arms to raise the closures 32. On the other hand, the unit comprising the closures 32, the rods 33, the frame 34 and the rollers 35 may gravitate to its lowered position or, if desired, may have suitable spring means connected therewith to assist in moving it to its lowered position when the cam arms are swung to permit it to move downwardly. In fact, there may be positive connections between the cam arms 36 or their equivalents and the closures 32 whereby the latter are positively moved downwardly as well as upwardly.

While plastic material may be supplied to the mold box B in any suitable manner, means preferably is provided as a part of the machine for supplying a measured amount of material to said box during each cycle of operation of the machine. In this connection and as illustrated in the present instance, a hopper 39 to contain the plastic material is located rearwardly of the mold box above the plate 20, and an open-top, open-bottom pan 40 is shiftable over said plate and over the top of the mold box between a position underlying said hopper and a position overlying said mold box.

When the pan 40 underlies the hopper 39, material may be supplied thereto from said hopper and the material will be prevented from passing through said pan by the plate 20 underlying the same. On the other hand, when said pan is shifted into overlying relationship to the open top of the mold box B, the material contained in said pan will gravitate through the open bottom thereof into the mold box. Extending rearwardly from the pan 40 at the top thereof is a plate 41 which moves beneath the hopper 39 and cuts off flow of material therefrom as the pan is shifted from its position beneath said hopper to its position overlying the mold box. Manifestly, therefore, a measured amount of material is supplied to the mold box B each time the pan 40 is shifted.

While any suitable means may be provided for shifting the pan 40, a simple, practical means for this purpose may consist, as shown of a lever arm 42 pivoted at a suitable point to the frame A for forward and rearward swinging movements and connected to said pan by suitable links 43. In this connection, both the lever arm 42 and the lever arm 38 preferably are located adjacent to one another near the front end of the machine so as to be in convenient reach of an operator standing in front of the machine.

It is desirable that the pan 40 remain above and be shaken with the mold box during shaking of the latter to feed material thereto as the material therein settles and densifies. Therefore, it is further desirable to provide means to temporarily fasten said pan securely to mold box in overlying relationship thereto, not only to insure shaking of said pan with the mold box, but to avoid undesirable looseness and rattling of said pan. In this connection it will be noted that the mold box is surrounded and reinforced at its top by angle-iron members 44, and that the flanges of these members serve as supports for the pan

40 when said pan is disposed in overlying relationship to said mold box. It will further be noted that strips 45 overlie the outer marginal portions of the flanges of the angle-iron members 44 at the sides of the mold box and also the marginal side portions of the plate 20 and serve as guides to provide a slideway for the pan 40 and to hold the latter against lateral movement relative to said plate 20 and the mold box. 10 In addition, it will be noted that rods 46 are spaced above and overlie the guide strips 45 and that lugs 47 project from the sides of the mold box between said strips 45 and said rods 46. It is apparent, therefore, that by downward movement of the rods 46 the lugs 47 may be clamped between said rods 46 and the strips 45 to fasten the pan 40 securely to the mold box B.

The rods 46 are suitably fastened at their rear ends to the plate 20 and at their front ends are 20 provided with downwardly directed lugs 48, while fastened to the front end of the mold box B, midway between its sides and near its top, is a lug 49. Extending transversely across the front end of the mold box B and through the lugs 48 and 49 is a rod or shaft 50 which medially is slightly bent so that it is of shallow V-shape and therefore is in the nature of a crank, and which is provided with a suitable handle 51 for effecting its rotation. Accordingly, by rotating said shaft to a given angular position, the rods 46 may be lifted at their front ends and the pan-carried lugs 47 will be free to slide between the strips 45 and said rods 46. On the other hand, by rotating said shaft to another angular position, the rods 46 25 may be drawn downwardly to clamp the lugs 47 between the same and the strips 45 and thus fasten the pan 40 securely relative to the mold box.

In the operation of the machine, the pan 40 is shifted from beneath the hopper into overlying relationship to the mold box B to supply material to the latter. The pan 40 then is clamped to the mold box and the motor 22 is operated for the required period of time to obtain desired densification of the material in the mold box, which densification is greatly expedited by the three-point resilient suspension of the mold box and the resilient suspension of the cores 29 relative to said mold box. The pan 40 then is released and returned to its position beneath the hopper 39 to receive a fresh charge of material therefrom and the closure 32 for the bottoms of the mold box compartments are raised to lift the formed blocks from the mold box. The blocks then are removed from the closures 32 and the latter are returned to their lower positions, whereupon the machine is readied for a subsequent cycle of operation. 45

From the foregoing description considered in connection with the accompanying drawings, it is believed that the construction and operation of the machine will be clearly understood and its advantages appreciated. It is desired to point out, however, that while only a single, specific structural embodiment of the invention has been illustrated and described, the same is readily capable of various specifically different structural embodiments within its spirit and scope as defined in the appended claims.

I claim:

1. A machine for molding blocks from plastic material comprising a mold box, means resiliently supporting said mold box at only three spaced points, and means for shaking said box.

2. A machine for molding blocks from plastic material comprising a mold box, means resiliently supporting said box at not more and not less than

three spaced points, cores within and resiliently supported by said mold box, and means for shaking said mold box.

3. A machine for molding blocks from plastic material comprising a rigid frame, a mold box, a leaf spring extending transversely relative to said frame and supported at its ends thereon, a supporting connection between said mold box at one end thereof and a medial portion of said spring, a pair of spring arms between said frame and said box supporting the latter at its other end and adjacent to opposite sides thereof, respectively, and means for shaking said box.

4. A machine for molding blocks from plastic material comprising a resiliently supported open-top mold box including a plate flush with its top and extending beyond one end thereof, an open-bottom pan slideable from a material-receiving position overlying said plate to a position overlying said mold box for delivery of material therefrom to the mold box, lugs extending from the sides of said pan, rods overlying said lugs, means for drawing said rods downwardly to clamp said pan to said mold box, and means for shaking said mold box and said pan.

5. A machine for molding blocks from plastic material comprising a rigid frame, a mold box, spring means resiliently supporting said box medially at one end upon said frame, other spring means resiliently supporting said box at its other end and adjacent to its sides, respectively, upon said frame, and means for shaking said box.

6. A machine for molding blocks from plastic material comprising a rigid frame, a mold box, spring means resiliently supporting said box medially at one end thereof, a pair of vertically disposed spring arms having laterally disposed lower ends fastened to said frame and laterally disposed upper ends supporting said mold box at its other end and adjacent to the sides thereof, respectively, and means for shaking said box.

7. A machine for molding blocks from plastic material comprising a resiliently supported open-top mold box including a plate flush with its top and extending beyond one end thereof, an open-bottom pan slideable from a material-receiving position overlying said plate to a position overlying said mold box for delivery of material therefrom to the mold box, lugs extending from the sides of said pan, rods overlying said lugs, said rods each being secured at one end to said mold box and having its other end free for upward and downward movement, a bowed shaft extending transversely of said mold box and rotatably mounted at a medial point thereon and connected adjacent to its ends to the free ends of said rods for rotation to draw said rods downwardly against said lugs and thus clamp said pan securely to said mold box for vibration therewith, and means for vibrating said mold box.
